METHOD AND APPARATUS FOR HANDLING
AIRPLANES FOR REFUELING

Walter C. Leitch, Springfield, and Joseph A. Logan, Hadley, Mass., assignors to Gilbert & Barker Manufacturing Company, West Springfield, Mass., a corporation of Massachusetts

Application February 10, 1945, Serial No. 577,322

3 Claims. (Cl. 244—114)

1

The invention to be described is a new method for helping the work around an airplane when it is on the flying field. For example, the work of refueling. Such work is now difficult. It is difficult because both safety and speed are so important. The difficulty is increased by large size airplanes needing thousands of gallons in one filling operation. The new method is very useful for many operations around a large plane, apart from the refueling one. To help the work of this one, however, is a leading purpose of the invention.

Prior ways of carrying on refueling operations are generally known and need not now be reviewed. There seems to be one general difficulty in that the various prior ways are not well adapted to fast and safe work. This is particularly true with respect to fueling the large planes.

The new method will be understood by the description of the way it is carried out on a flying field by the tools or structure, all as indicated in the drawings.

Referring to the drawings:

Fig. 1 is a somewhat diagrammatic view of a flying field, its main building and several service positions, or stations, each for one plane needing servicing work;

Fig. 2 is a view generally in section at one of the service positions, or stations, viewed with a plane in position for being serviced; and

Fig. 3 is a similar view at right angles to that of Fig. 2.

The method of handling the plane is one for working on the flying field. Fig. 1 shows such a field with four work stations on it. They are grouped around the main building shown. The work at each station is the same.

When a plane lands it goes immediately to an assigned station. The plane is shown just as it is first positioned at station 1. It rests on elevator platform 5. The platform is level with and forms a small part of the flying field. There are no obstructions. The plane is rested on the platform area as easily as if such area were merely marked off on the field.

The relation of the plane to the platform is shown by way of example at stations 1 and 2 of Fig. 1 and by Figs. 2 and 3. A feature is that the platform is large enough to directly underly the cabin, or the major part of the carrying space for passengers and freight, but is not large enough to directly underlie the wings and tail parts. The idea is to lower the cabin into the ground to bring the wings close to the ground. The positions they are moved to by the platform are in-

2

dicated by way of example. At stations 3 and 4 of Fig. 1, the platform is shown without the plane, in lowered and raised positions respectively.

The method is particularly applicable for handling a large plane, for example as high as an ordinary house or higher. The plane indicated is one of the large ones. In the position of Figs. 2 and 3, the wings W have been positioned within easy reach of the ground. They can be mounted with ordinary step ladders or without any ladders and access to their fuel tank openings is obtained with speed and safety.

Consider Fig. 2, the fuel dispensing hose 6, stored underground in a room or tunnel connected with the elevator pit, is shown fueling the plane through four hose lines. All hose is quickly placed in position, the fuel delivered, and the hose put back underground. In this work, the length of hose, its weight, and the distance the workman needs to carry it are all brought into a small scale. The scale is reduced to a remarkable extent from the fueling equipment now used to service large planes. This results in making the work easier for the men and therefore makes it much safer. This result is made feasible by the new way the large plane is handled.

The hose lines, the reels for them, the dispensing line pump are sufficiently indicated in Fig. 2 for the purpose of understanding the method. Such equipment can be used of course in many different forms. So too, greasing equipment 7 and the like is indicated. The elevator pit may be connected to underground storage space such as a room or tunnel 9. The workmen can operate on the plane with all appropriate service station equipment, as line pump 10, as will be obvious from what has been stated.

The way described for handling the plane for fueling purposes is useful for many other operations. I will describe some of these and analogous operations will readily be apparent without specific description.

Fig. 1 shows the plane stations 1, 2, 3, and 4 as connected to the main building 20 by several tunnels 9. When the plane is lowered straight into the ground at a station on the flying field area, these tunnels may connect the plane adjacent its door openings. Passengers and freight can be unloaded and loaded from some tunnels and workmen to service the plane can operate with equipment taken out of other tunnels. They can work underground and above ground without the movement of passengers or freight interfering. The area of the flying field all around the plane may be kept entirely clear of all but

authorized workmen. There need be no traffic on such area as there normally is around a plane at its air field station.

An advantage of the method in handling the plane stationed on the flying field not only for fueling purposes but also for the other operations is this. The waiting time of the plane between its landing and taking off at the field can be substantially cut down. This will be clear from considering the illustrative examples of Fig. 1 indicating different operations all of which contribute to shorten the waiting time at a station.

The method has been described in relation to the use of civilian airplane facilities. Its relation to military airplanes will be briefly referred to. In this relation the question of fast and safe fueling operations for very large planes is important. They carry accessory mechanism on the wings. They are endangered if the plane is not carefully handled in fueling operations. The planes have become so large that the need for improved fueling methods has reached an acute stage. This is true not only with regard to speed of operation but also with regard to safety of operation for the man and for the plane. The ordinary rate of gasoline dispensing systems is altogether too slow. The bulk delivery systems of faster rates are not adapted for location inside the flying field. Of course underground piping systems in general would occur to any one. But the difficulty has been to provide for the delivery end of such systems. With the plane on the field carrying its filling tank openings thirty feet and often much more above the ground, it ordinarily takes something on the order of a well equipped city fire department with hose wagons, long ladders, and dangerous work to get the gallonage into the plane at anywhere near the desired speed. The plane usually has deicing mechanism along the wing edges. The wings carry other accessory mechanism. It is dangerous for both men and for plane equipment when long ladders are used to reach and work around the wings.

In this situation prior efforts of improvement have involved improvements in the fueling equipment. The invention of the present method in contrast involves the handling of the plane. It can be used along with many of the improvements in the fueling equipment per se. But the new method from one aspect operates to make the fueling of a large size plane as easy for the most part, as if it were a small size plane. This is true with respect to the position of easy reach from the ground, in which the wings and the filling openings are easily reached from the ground around the wing edges.

The elevator used for carrying out this method needs to be of much less area than the area needed to take the whole spread of the plane. The elevator is used to manage the plane, to bring its wings close to the ground. The particular plane with relation to platform area is just by way of example. Other types of planes may need other types of platforms to carry out the idea. While it is very useful to then fuel the plane from underground equipment as already indicated, this is not necessary to the broadest aspect of the invention. For example, consider that the plane at station 1 has had its cabin lowered with the platform into the elevator pit. Then its wings will have the position close to the ground, as the plane wings indicated at station 2 and in Fig. 2 with more detail. In this position any tank wagon truck

can operate on the field, draw along side of the wing, dump its load into one of the wing tanks, and use just the ordinary hose and dispensing equipment of the tank truck and with all ordinary safeguards in the handling of gasoline. But such an operation would not be possible if the method were not used by the relatively small elevator to handle the plane and lay its wings over the ground at practically the level of the tank wagon. This example illustrates the fact that all the equipment and facilities of the drawings and description are not necessary to the broad aspect of the method of improvement in the fueling of large planes. The prior art methods now cause much fueling trouble at flying fields. A prime feature of the method is the elevator platform size with relation to taking the cabin but not the wings into the ground while placing the wings in the right relation to the ground so as to work from the ground around the low leveled wings.

The elevator controls and operating means have not been shown as such things are too well known to need description. But for a safeguard to the plane in the use of the method, a special safety switch may be used in Fig. 1. It may operate from a padded rod engaging the wing as the plane is lowered. The safety switch may be opened as the rod is lowered a small distance at the end of the downward movement of the wing. The opened switch may stop the elevator as a control switch. This switch may be closed automatically or by-passed by a circuit closed when the usual elevator switch is operated to move the platform and plane up. This is not a feature claimed herein. It is pointed out as a desirable piece of safety equipment within the scope of any electrician's ability to install once he has the idea. By setting a safety switch rod, one preferably under each wing, at about the level desired for locating the wings at low level position, different sized planes handled by the same elevator will be protected against going too far down.

We wish to emphasize the time saving and safety features of the method in the use for which it is adapted.

It will be appreciated that with so many different types of planes in use there may be various changes in the particular arrangement of platform areas on air fields. The illustration shown discloses the method. It can be carried out with a good many different kinds of equipment and flying field arrangements.

The claims for the invention are:

1. The method of handling a plane for servicing on a flying field, which comprises moving the plane onto a support at field level, the surface width of the support being confined to substantially the overall maximum width dimension of the underwing structure of the plane being serviced, and lowering the support below ground level to a depth sufficient to bring the wings of the plane into service accessible proximity to the surface of the flying field.

2. Apparatus for servicing a plane on a flying field which comprises a pit having a maximum width dimension not substantially greater than the overall width dimension of the underwing structure of the plane to be serviced, a platform having an unobstructed surface and forming a closure for the surface opening of the pit flush with the surface of the flying field, said platform being movable inwardly of the pit, and means to lower said platform to position the wings of a plane supported on said platform into service

accessible proximity to the field surface at the sides of the pit.

3. Apparatus for servicing a plane on a flying field which comprises a pit having a maximum width dimension not substantially greater than the overall width dimension of the underwing structure of the plane to be serviced, a platform having an unobstructed surface and forming a closure for the surface opening of the pit flush with the surface of the flying field, said platform being movable inwardly of the pit, means to lower said platform to position the wings of a plane supported on said platform into service accessible proximity to the field surface at the sides of the pit, and chambers opening from the side walls of the pit affording servicing, loading and unloading access to the underwing structure of the plane within the pit as it rests on the so lowered platform.
